CLAIM

The ornamental design for a rotor for fishing reel, as shown and described.

DESCRIPTION

FIG. 1 is a perspective view of front, left and bottom side of a rotor for fishing reel showing our new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof; and,

FIG. 8 is a side view of the design shown in use.

The portions of the article in broken lines are shown for illustrative purposes only and form no part of the claimed design.
